(57) **CLAIM**

The ornamental design for a lighting device, as shown and described.

DESCRIPTION

FIG. 1 is a front perspective view of a lighting device showing the new design;

FIG. 2 is a rear perspective view thereof;

FIG. 3 is a front side elevational view thereof;

FIG. 4 is a rear side elevational view thereof;

FIG. 5 is a right side elevational view thereof;

FIG. 6 is a left side elevational view thereof;

FIG. 7 is a top plan view thereof; and,

FIG. 8 is a bottom plan view thereof.

FIG. 9 is a front perspective view of the lighting device installed in a first example cradle; and

FIG. 10 is a rear perspective view thereof.

FIG. 11 is a front perspective view of the lighting device installed in a second example cradle; and

FIG. 12 is a rear perspective view thereof.

FIG. 13 is a front perspective view of the lighting device installed in a third example cradle; and,

FIG. 14 is a rear perspective view thereof.

The broken line showing of the cradle in FIGS. 9–14 is directed to environment. All other broken lines represent portions of the article not claimed. The broken lines form no part of the claimed design.

1 Claim, 14 Drawing Sheets
